MAGNETIC DISK STORAGE CARTRIDGE

Donald A. Moore, Los Gatos, Calif., assignor to International Business Machines Corporation, Armonk, N.Y., a corporation of New York

Filed Oct. 21, 1965, Ser. No. 87,660

Term of patent 14 years

(Cl. D26—14)

FIG. 1

FIG. 2

FIG. 3

FIG. 4

FIG. 5

FIG. 1 is a top view of a magnetic disk storage cartridge showing my new design;

FIG. 2 is a bottom view thereof;

FIG. 3 is a front elevation view thereof taken along lines 3—3 of FIG. 1;

FIG. 4 is a side elevation view thereof taken along lines 4—4 of FIG. 1, the opposite side being substantially a mirror image thereof; and

FIG. 5 is a rear elevation view thereof taken along lines 5—5 of FIG. 1.

I claim:

The ornamental design for a magnetic disk storage cartridge, as shown and described.
